(57) **CLAIM**

The ornamental design for an accessory module for headset, as shown and described.

DESCRIPTION

FIG. 1 is a front view of an accessory module for headset, showing our new design.

FIG. 2 is a rear view of the thereof;

FIG. 3 is a right side view thereof;

FIG. 4 is a left side view thereof;

FIG. 5 is a top view thereof;

FIG. 6 is a bottom view thereof;

FIG. 7 is a top-rear-right perspective view thereof;

FIG. 8 is a bottom-rear-left perspective view thereof;

FIG. 9 is a top-front-left perspective view thereof;

FIG. 10 is a bottom-front-right perspective view thereof;

FIG. 11 bottom-rear-left perspective thereof; showing the module, in a condition of use, with the headset inserted into the accessory module; and,

FIG. 12 top-front-right perspective view thereof; showing the module in a condition of use, with headset inserted into the accessory module.

The shade lines show surface contour and not surface ornamentation.

The broken line showing of internal components of the accessory module illustrates environmental structure, and the broken lines form no part of the claimed design.
